UNITED STATES PATENT OFFICE.

THOMAS L. LEE, JR., OF WESTFIELD, NEW JERSEY, ASSIGNOR TO THE HALL SIGNAL COMPANY, A CORPORATION OF MAINE.

ELECTRIC-CIRCUIT-CONTROLLING APPARATUS.

1,024,588.

Specification of Letters Patent. Patented Apr. 30, 1912.

Application filed February 12, 1910, Serial No. 543,540. Renewed December 19, 1911. Serial No. 666,640.

To all whom it may concern:

Be it known that I, THOMAS L. LEE, Jr., a citizen of the United States, residing at Westfield, in the county of Union and State of New Jersey, have invented certain new and useful Improvements in Electric-Circuit-Controlling Apparatus, of which the following is a specification, reference being had therein to the accompanying drawings, 10 forming part thereof.

My invention relates broadly to contact devices for opening and closing electric circuits, and it is the broad object of my invention to produce an efficient contact-making device which will insure a large surface of contact and low contact resistance.

More particularly my invention relates to the circuit controlling contact devices employed in electrically-controlled relays in 20 railway signaling systems.

In many instances it is permissible to employ two metal contact devices for opening and closing an electric circuit. But the contact devices operated by the relays employed to control railway signals are liable to heavy currents from lightning discharges; and if the contact devices should become fused or welded together by an excessive current from lightning or any other cause, they could thus maintain closure of the circuit which they control at a time when this circuit should be open, and might thus cause a false clear signal to be given which would introduce great hazard to traffic. To avoid this hazard, it has been common to employ contact devices at least one of which is made of an infusible material. Graphite or some form of carbon is almost universally used, and this material generally introduces too much contact resistance into the circuit which it controls, especially after being used for some time, when its contact surface becomes glazed or polished.

A specific object of my invention is to overcome the excessive contact resistance which has heretofore been involved in the use of carbon contacts.

To the foregoing ends my invention comprises broadly a contact device such as above referred to, of flexible yielding character, which enables it to conform to the surface of its co-acting contact device and thus make efficient contact throughout a relatively great contact surface.

In the specific embodiment of my invention which I have illustrated in the accompanying drawings, this flexible and conforming attribute of the yielding contact device is attained in a flexible device held under tension or tensile strain between two flexible arms which support it, so that when applied laterally to its co-acting contact device it will tend to curve or wrap around the unyielding surface thereof.

My invention broadly comprehends, though it is not limited to, a contact device having a rough, broken or interrupted surface, or surface presenting prominent lines or points of contact, and co-acting with a second contact device which it engages so as to bring said prominent lines or points into effective circuit-making contact therewith, said second contact device being of carbon or some material which will be relatively soft or quick wearing so that the prominent points on the rough or broken contact surface will wear contact recesses into the relatively quick-wearing material and thus increase the area of contact.

My invention also comprehends, broadly, a contact device with openings in its surface through which may fall or escape the minute dust or particles worn off from its co-acting contact device, such as a graphite electrode.

My invention also broadly comprehends a number of conductive wires collectively employed as a contact device, preferably flexible and stretched between elastic supports and making lateral contact with a co-acting device of relatively soft or quick wearing material; and more specifically my invention contemplates the embodiment of this feature in flexible wire gauze. However, as to a stretched flexible contact device, movable only, relatively, toward and from a second contact device, my broad invention is not limited to wire gauze or to any rough or broken surface, as in some cases it might well be a smooth metal ribbon.

Other features of my invention will appear in the following description of that particular embodiment which I have illustrated in the accompanying drawings, in which,

Figure 1 is an elevation of a signal-controlling relay, showing the carbon and wire-gauze contact devices in effective engagement; Fig. 2 is an elevation of the electric

bow and the gauze stretched out straight by the bow, as when the gauze is out of contact with the carbon contact device; and Fig. 3 is a plan view of the gauze and the elastic bow in which it is mounted.

The armature proper A is mounted upon a suitable pivot B in position to be attracted by the electro-magnet C. An arm or finger D is suitably mounted on the armature and 10 carries an elastic or spring bow E bent up from any suitable flat metal stock and carrying the flexible wire gauze F stretched between its ends. The gauze may be made of platinum, silver or other suitable conductive 15 wire. When the armature is raised, the upper face of the gauze is pressed laterally against the contact surface of the graphite or carbon contact member G, which may be mounted in any suitable manner. The flexibility and elasticity of the gauze and carrying bow cause the gauze to slightly bend or wrap around the bottom surface of the graphite contact, which is preferably slightly convex, whereby the gauze conforms to this 20 convex surface and effects contact therewith over a relatively great surface and at many points. After the gauze has been used for some time, the wires of the gauze will wear slight recesses in the surface of the relatively soft or quick-wearing graphite, thereby increasing the contact surface and causing the contact resistance to be reduced, rather than increased, by continued use of the relay; while the dust or fine particles of 25 graphite thus worn off fall through the mesh of the gauze and hence do not in any way interfere with the operation of the device. In this particular construction, the spring bow E is riveted or otherwise secured at its middle point to the finger D and the ends of the bow are bent in double to form a clamping surface between which the ends of the gauze are riveted. Graphite is generally the best material for the contact G.

Manifestly the broad features of my invention may be embodied in various modifications, all coming, however, within the spirit and scope of my invention broadly.

50 I claim:

1. Electric circuit-controlling apparatus comprising two contact devices movable only toward and from each other, one of such contact devices having a flexible contact surface yieldingly held under tension.

2. Electric circuit-controlling apparatus comprising a contact device with a relatively soft surface, a second contact device with a rough, broken or interrupted surface adapted to wear contact recesses into the soft surface of the first said device, and means for pressing said devices together.

3. Electric circuit-controlling apparatus comprising a flexible contact device under tension and having a rough, broken or in-

terrupted contact surface, a second contact device with a relatively soft surface, and means for pressing the two devices together to bring the second device into contact with the prominent points on the surface of the flexible device.

4. Electric circuit-controlling apparatus comprising a contact device with a relatively soft or quick wearing surface, a second and flexible contact device having a rough, broken or interrupted surface adapted to wear contact recesses into the soft surface of the first contact device, and means for pressing the contact devices together.

5. Electric circuit-controlling apparatus comprising two contact devices movable only toward and from each other, one contact device of relatively soft or quick wearing material, and the other contact device having a yielding flexible contact surface adapted to conform itself to the surface of the first contact device and to wear contact recesses into the soft surface of the first contact device.

6. Electric circuit-controlling apparatus comprising one contact device with a relatively soft surface, a second contact device consisting of a conductive wire gauze held between suitable mountings, and means for bringing said gauze into lateral contact with the first said contact device.

7. Electric circuit-controlling apparatus comprising one contact device, a second contact device consisting in a flexible conductive wire gauze stretched between elastic flexible mountings, and means for effecting lateral contact of said gauze with the first said contact device.

8. Electric circuit-controlling apparatus comprising one contact device of relatively soft or quick-wearing material, a second contact device including a flexible conductive wire gauze stretched between suitable elastic mountings, and means for pressing said gauze laterally against the surface of the first said contact device.

9. Electric circuit-controlling apparatus comprising one carbon contact device, a second contact device including a flexible conductive wire gauze stretched between suitable elastic mountings, and means for pressing said gauze laterally against the carbon contact device.

10. Electric circuit-controlling apparatus comprising one contact device, a second contact device including an elastic bow suitably mounted and a flexible conductor stretched between the ends of the bow, and means for bringing the flexible conductor into lateral contact with the first said contact device.

11. Electric circuit-controlling apparatus comprising one carbon contact device, a second contact device including an elastic bow mounted at the middle and a wire gauze stretched between the ends of the bow, and

- means for bringing the gauze into contact with the carbon device.
12. Electric circuit-controlling apparatus comprising a carbon contact device, an electro-magnet, an armature operated thereby, an elastic bow mounted on a suitable connection with the armature, and a flexible wire gauze stretched between the ends of the bow in position to press laterally against the carbon contact device when the armature occupies one position.
13. Electric circuit-controlling apparatus comprising a relatively soft or quick-wearing contact device, a second contact device co-acting therewith and having openings in its surface through which may escape the worn-off particles of the first said device, and means for pressing said devices together.
14. Electric circuit-controlling apparatus comprising a carbon contact device, a second contact device with a yielding flexible contact surface adapted to conform itself to the surface of the carbon contact device, and means for pressing the contact devices together.

In testimony whereof I have affixed my signature in presence of two witnesses.
